LAMP BASE AND SOCKET

Arthur B. Oday, Cleveland Heights, Ohio, assignor
to General Electric Company, a corporation of
New York

Application May 3, 1944, Serial No. 534,006

3 Claims. (Cl. 176—29)

1

My invention relates to electric lamps of the elongated, double-ended type having a bi-pin base at each end for engaging with spaced sockets between which the lamp is supported. Such lamps are now well known in commerce, one variety being the fluorescent, positive column, discharge lamp having filamentary electrodes which are preheated during starting of the lamp.

In the development of such fluorescent lamps, the non-luminous base was kept to minimum depth, the pins thereon to minimum length and the sockets of minimum depth or thickness to minimize the dark spaces between the luminous portion of aligned lamps mounted in end-to-end relation. Millions of lamps and sockets so constructed have been sold and installed. In many installations, however, the lamps are mounted in spaced, parallel position rather than in end-to-end relation. The length of the base pins and the thickness of the socket, thus, could be selected to suit needs and requirements other than those which determined the dimensions of these members in the development of the lamp for end-to-end mounting. For example, the tolerances in the spacing of the sockets which are necessarily rather close with present commercial sockets and lamps designed primarily for end-to-end lamp mounting could be substantially increased in the parallel mounting of the lamps by making the base pins longer and the bases thicker. The advantages of larger tolerances for mounting spaced sockets in lamp fixtures are substantial and important, resulting in the saving of time and expense in the fabrication and assembly of such articles.

Obviously, however, increasing the length of the base pins of the present lamps, which lamps are made of standard over-all length measured between the ends of the base pins at opposite ends of the lamps, would prevent the introduction of the lamps into sockets now installed in existing fixtures. Of course, it is possible to provide some lamps with longer pins than those on the present lamps but this would multiply the number of standard length lamps by a factor of two and result in complications in making, storing and ordering the lamps which are highly desirable to avoid.

The principal object of my invention is to provide lamps of standard overall lengths which may be used interchangeably with existing lamp sockets and with sockets of substantially greater depth or thickness permitting larger tolerances in socket spacing than is possible with existing sockets. Another object of my invention

is to provide a new socket and a new base for elongated double-ended, electric lamps and providing greater contact area between engaging parts. Further objects and advantages of my invention will appear from the accompanying drawing and the appended claims.

In the drawing:

Fig. 1 is a side elevational view of a conventional simple type of fixture supporting a conventional lamp; Fig. 2 is a front elevational view of a conventional socket; Fig. 3 is a sectional view along the line 3—3 of Fig. 2 and showing one end of a lamp secured in the socket; Fig. 4 is a perspective view of my new base; Fig. 5 is a top, partly sectional view similar to Fig. 3 of a socket and lamp base embodying my invention and Fig. 6 is a similar view of my new base mounted in a conventional socket.

Referring to Figs. 1 and 2, the fixture illustrated 20 comprises a hollow, elongated, ballast and current wire accommodating housing 10 having mounted thereon a pair of spaced sockets 11 which are provided with a slotted shoulder 12 accommodating fastening bolts 13. The housing 10 also supports the usual starter 14. The sockets 11 are spaced sufficiently to accommodate and support therebetween a double-ended lamp 15 which may be a fluorescent lamp of the type well known in commerce. Such lamps have at 30 each end a bipin or two prong base 16, shown in Fig. 3. The pins 17 and 18 on each base 16 are coplanar with those on the other base 16 of the lamp 15. The lamp 15 is mounted between the sockets 11 by moving it transversely 35 to its longitudinal axis into the space between said sockets 11 with the pins 17 and 18 held in alignment with a straight slot 19 (Fig. 2) in each of the sockets 11. The lamp is then rotated 90° to move the pins 17 and 18 into arcuate slots 20 and 21 on either side of the straight slot 19 of the socket. The pins 17 and 18 then engage spring contacts 22 and 23 housed in the electrically insulating parts of socket 11 and disposed in slots 20 and 21, respectively. The contacts 45 22 and 23 resist any tendency of the lamp 15 to rotate in the sockets 11. The straight slot 19 and the arcuate slots 20 and 21 are defined, in part, by a stud 24 which consists of two spaced parts, lunette shaped in transverse section, secured to and extending from the rear wall of the socket recess to the front face of a socket cover 50 25 as shown in Fig. 3.

The lamp and sockets of the type shown in Figs. 1 to 3 and described above are well known in commerce, are disclosed in the Marshaus Re-

issue Patent 21,545 of August 27, 1940, and have been included herein for the purpose of contrast between the present base and socket structure and my new base and socket structure shown in Figs. 4, 5 and 6.

In Fig. 4 the new lamp base 28 is shown out of a socket and in Fig. 5 inserted in my new socket. As shown, the base 28 comprises pins 26 and 27 which are longer than the pins 17 and 18 of the conventional base 16 shown in Fig. 3 and an electrically insulating member 29 which is located between the said pins 26 and 27. The insulating member 29 is of sufficient depth or thickness, measured from the surface of the base outward, that the part of the pins 26 and 27 extending beyond member 29 is equal in length to that of the exposed portion of pins 17 and 18 of the base 16 (Fig. 3). Lamp bases of the type shown in Fig. 4 may be inserted in conventional sockets in the conventional manner described above and when so inserted the member 29 is in position to butt against the stud 24 as shown in Fig. 6. The possible displacement of the lamp 15 longitudinally thus is limited by member 29 so that the pins 26 and 27 at either end of the lamp cannot be moved out of the conventional socket in the direction of the longitudinal axis of the lamp 15.

Of course, the overall length of the lamps provided with the new bases, that is, the distance between the ends of the pins at opposite ends of the lamp, must be the same as that of the lamps provided with the present commercial bases in order to be mountable in commercial sockets now installed. This may be achieved by merely shortening the glass envelope of the lamp 15 a distance equal to the increase in the length of the pins 26 and 27 at each end of the lamp. For example, if the length of the pins 26 and 27 on each lamp base is increased one-eighth of an inch the lamp envelope is made one-quarter inch shorter to make the overall length of the lamp the same as that of present commercial lamps.

The new base is also engageable with sockets of the type shown in Fig. 5 which are similar, except as noted below, to the sockets shown in Figs. 1 to 3. The stud parts 30 and 31 of the socket shown in Fig. 5 are the same in length as the studs 24 of the conventional sockets shown in Figs. 1 to 3 but the main body portion of the socket is greater in depth or thickness so that these stud parts terminate appreciably short of the outer face of the cover 25. The contacts 32 and 33 of the socket shown in Fig. 5 are of greater width than that of the contacts 22 and 23 of the sockets shown in Fig. 3 and extend from the end of parts 30 and 31 toward the back wall of the socket recess. The area of contact between the pins 26 and 27 and contacts 32 and 33 is thus substantially greater than that between the pins 17 and 18 and the contacts 22 and 23 of the sockets of Figs. 1 to 3 and the effective physical and electrical connection between the lamp base and the socket is greater. The increased width of the contacts 32 and 33 makes it possible to depart a

greater distance from the closest possible spacing of the sockets when the new rather than the conventional sockets are used. For example, if the width of the contacts 32 and 33 is one-eighth inch greater in the new socket than in the conventional socket, then the sockets may be spaced one-quarter of an inch farther apart than conventional sockets without risk of the lamp falling out of the socket or the contact pins on the lamp base failing to engage the spring contacts of the socket.

Thus, my new base and socket effectively engage each other to provide good electrical contact and physical support for the lamp without the requirement of the close tolerances in socket mounting heretofore necessary with conventional sockets and bases.

What I claim as new and desire to secure by Letters Patent of the United States is:

1. In combination, an elongated electric lamp having a base at each end and a pair of spaced sockets supporting said lamp; each of said lamp bases comprising two spaced, outwardly projecting, parallel, socket engaging, contact pins and another, shorter projection on said base between said pins which is of small height compared to the length of said pins; each of said sockets comprising an electrically insulating housing provided with a recess and a stud upstanding from the bottom of said recess to define with the walls of said recess an arcuate slot accommodating said base pins; spring contact members disposed in said slot, engaging said base pins and extending from the free end of said stud toward the back wall of said recess, said stud terminating short of the outer face of said socket a distance substantially equal to the height of said projection on said lamp base and serving as a stop engageable with the shorter projection on said lamp base to limit longitudinal movement of said lamp in said sockets.

2. A lamp base comprising a shell having contact pins projecting outward from the bottom thereof, and an embossment on the bottom of said shell bridging the space between the opposed inner sides of said pins and being of small height compared to the length of the said pins, the outer sides of said pins being exposed for their full lengths.

3. An elongated electric lamp having bases at its ends for engaging a pair of sockets, each of said bases comprising a shell having parallel contact pins projecting outward longitudinally of the lamp from the end of said shell for engaging contacts in a socket, and an embossment on the end of said shell bridging the space between the opposed inner sides of said pins, the outer sides of said pins being exposed for their full lengths, the said embossment being of small height compared to the length of the said pins, whereby the embossments serve to limit relative movement between the lamp and the sockets longitudinally of the lamp.

ARTHUR B. ODAY.
